UNITED STATES PATENT OFFICE.

JOSEPH B. NEWMAN, OF RAVENNA, KENTUCKY.

MOUTHPIECE FOR MUSICAL INSTRUMENTS.

Application filed January 22, 1924. Serial No. 687,804.

To all whom it may concern:

Be it known that I, JOSEPH B. NEWMAN, citizen of the United States, residing at Ravenna, in the county of Estill and State 5 of Kentucky, have invented certain new and useful Improvements in Mouthpieces for Musical Instruments, of which the following is a specification.

This invention relates to mouth pieces for 10 musical instruments, such as cornets, trombones and the like.

In order to properly and satisfactorily master the playing of cornets, trombones and like musical instruments, it is very essential 15 that no appreciable pressure of the lip be placed upon the cup of the mouth piece such as would cause movement of the mouth piece cup toward and onto the stem of the mouth piece were they slidably associated. One of the main reasons for failure 20 of persons to properly master the playing of these instruments resides in the fact that they apply their lips to the mouth piece cup with considerable pressure in this manner and thereby are unable to properly 25 sound the notes or produce the proper tone.

It is accordingly an object of the present 30 invention to provide a mouth piece for instruments of the above kind by means of which playing of the instrument is absolutely prevented upon the application of a predetermined pressure of the lips upon the mouth piece cup.

A further object of the invention is to 35 provide means for permitting variation of this predetermined pressure so that the latter may be gradually decreased or initially set at any desired pressure for enabling a person to gradually master the playing of the instrument by a gradual reduction of the application of lip pressure to the mouth piece cup, and whereby the mouth piece may be set to suit the specific requirements met with in each individual case or person under 40 instruction.

A further object is to provide a mouth piece characterized as specified above and embracing the desired qualities of simplicity and durability of construction, as well 45 as efficiency in operation.

Still another object of the invention is to provide a mouth piece of the above kind that may be cheaply and easily manufactured and assembled, as well as placed into

use, and to provide means for facilitating 55 accurate adjustments for the purpose above mentioned.

Still another object of the invention is to provide a practice mouth piece of the above kind wherein provision is made for converting 60 the same into a rigid mouth piece when desired, such as after the proper playing of the instrument has been mastered.

With the above general objects in view 65 and others that will become apparent as the nature of the invention is better understood, the same consists in the novel form, combination, and arrangement of parts herein-after more fully described, shown in the accompanying drawing and claimed. 70

In the drawing, wherein like reference characters indicate corresponding parts throughout the several views:

Figure 1 is an elevational view of a mouth piece constructed in accordance with the 75 present invention.

Figure 2 is a substantially central longitudinal sectional view of the device shown in Figure 1, and

Figure 3 is a view similar to Figure 2, 80 showing a modification of the invention.

Referring more in detail to the drawing, the present invention consists of a mouth piece embodying a cup member 5 that is generally of conventional form, and a stem 6 85 upon the outer end of which the cup member 5 is mounted.

In accordance with the present invention the cup member 5 is slidably mounted upon the stem 6 for movement longitudinally 90 thereon, inward movement of the cup member 5 on the stem 6 being resisted by a compression spring 7, the pressure or strength of which may be adjusted by means of a nut 8 that is threaded upon the stem 6 for adjustment longitudinally of the latter. The outer end portion of the stem 6 is of a diameter slightly smaller than the central opening 9, provided in the cup member 5 so that,

under circumstances to be presently made apparent, air may pass between the stem and cup member to the atmosphere instead of being forced to pass through the hollow stem 6 or the bore of the latter, as indicated at 10, to thereby prevent playing of the instrument. 100

The cup member 5 is formed with an annular tapered or bevelled valve seat as at

11, concentric with and at the outer side of the opening 9, and adapted for seating upon this seat under the action of the spring 7 is a valve head 12 that is formed by a rigid 5 enlarged outer end portion of the stem 6. The helical compression spring 7 has its outer end disposed against an external annular shoulder 13 formed upon the cup member 5, and the inner end of the spring 7 10 is seated within a recess or groove 14 of the nut 8 formed by providing the latter between its ends with a peripheral flange 15 of T-shaped cross section as shown in Figures 2 and 3. One end of the nut 8 is inwardly tapered or bevelled as at 16 to conform to the shape of the cup member 12 surrounding the inner end of the opening 9 15 so that when the nut 8 is threaded along the stem 6 until the bevelled end 16 of said 20 nut engages the inner end of the cup member 5, a substantially rigid mouth piece will be had for use by one who has fully mastered the proper playing of the musical instrument. The flange 15 is disposed farther from the bevelled end 16 of the nut 8 25 than from the other end thereof so that said nut may be reversed upon the stem 6 for obtaining a maximum adjustment for thereby placing the spring 7 under maximum compression, if found necessary. The form of 30 the flange 15 provides another recess or groove 14' for reception of the inner end of the spring 7 in case the nut member 8 is thus reversed and for facilitating the turning of the nut 8, the periphery of the flange 15 is preferably roughened or knurled as 35 shown in Figure 1. The threads of the stem 6 engaged by the nut 8 may be interrupted for a small space so that a smooth longitudinal surface may be provided upon the 40 exterior of the stem 6 for the length of said thread for reception of graduations and cooperating progressing numerals as indicated generally at 17. This provides means 45 for facilitating minute and accurate adjustment of the nut 8 for an obvious advantage. Thus far described, the construction shown in Figures 2 and 3 are substantially alike except as to size of certain elements.

50 From the above description, it is apparent that should the lips be applied to the cup 5, with sufficient pressure to offset the action of the spring 7, said cup 5 will slide inwardly on the stem 6, so as to cause the valve head 12 to unseat or move away from the seat 11 of said cup 5, thereby allowing the air to pass to the atmosphere through the opening 9 and about the stem 6. This vents the air so that the same will not pass 55 through the bore 10 of the stem 6 and so that the musical instrument will accordingly not be played. In this manner, the person is prevented from playing the musical instrument unless he succeeds in placing the lip upon the cup member 5 with less

pressure than that required to overcome the action of the spring 7. By constant pressure, the person is able to accomplish this when the compression of the spring 7 is adjusted to a predetermined degree, and then 70 the nut 8 is slightly adjusted by threading the same toward the inner end of the stem 6 for reducing the strength of the spring 7 with regards to its pressure in causing seating engagement of the head 12 with the seat 75 11. The user of the mouth piece then is confronted with the necessity of practice for accomplishing playing of the instrument with slightly less pressure upon the lip cup 5, and this operation is repeated until the 80 nut 8 has been adjusted to substantially completely release the spring 7, at which time playing will be accomplished with practically no pressure applied by the lips 85 upon the cup member 5.

In the form of the invention shown in Figures 1 and 2, the stem 6 is formed in two sections, the outer section being threaded for reception of the nut 8, and the inner section being of relatively small diameter as indicated at 18 and having its inner end externally threaded for threaded engagement with the outer end of the inner stem section as indicated at 19, the bore of the section being similar. This permits ready assembly 90 or separation of the stem sections and other parts and further permits the use of a cup member 5, the opening 9 of which is relatively small, and the use of a stem section 18, the valve head 12 of which is correspondingly formed in size. After the stem section 18 has been passed through the opening 9 of the cup member 5, the same may have a lateral pin 20 secured thereto adapted to be received within a notch 21 provided in the inner end of the cup member 5 adjacent one side of said opening 9 when the cup member is forced toward the nut 8. When the projection 20 is disposed in the notch 21 the stem and cup member are held against relative rotation so that the nut 8 may be readily adjusted while the instrument is held in one hand and the other hand employed for turning the nut 8, the inward movement of the cup 5 being effected by applying lip pressure 100 thereon.

In the form of the invention shown in Figure 3, the stem 6 is formed of one piece, and in order to permit assembling of the stem 6 and cup member 5, the valve head 12 and opening 9 are necessarily made relatively large along with the seat 11. The advantage in this form of construction is that it reduces the number of parts of the mouth piece, but the form of the invention shown in Figures 1 and 2 is probably preferable due to the more practical size of parts and appearance.

From the foregoing description, it is believed that the construction and operation, 120

as well as the advantages of the present invention will be readily understood and appreciated by those skilled in the art.

What I claim as new is:

- 5 1. A mouth piece comprising a hollow stem provided at its end with a valve head, a nut mounted upon the stem, a cup slidably mounted upon the stem and having an interior surface engageable with the valve head and a cone shaped helical spring inter-
- 10 posed between the nut and the cup.

2. A mouth piece comprising a hollow stem having a valve head at its end, a cup slidably mounted upon the stem and having an interior wall surface which is spaced from the exterior surface of the stem and having an interior surface which engages the valve head, a nut mounted upon the stem and a cone shaped helical spring interposed between the nut and the cup. 15

In testimony whereof I affix my signature.

JOSEPH B. NEWMAN.
